UNITED STATES PATENT OFFICE.

HENRY LEVY, OF BROOKLYN, NEW YORK.

SMALL-BATCH-MIXING APPARATUS.

Application filed April 28, 1925. Serial No. 26,345.

My present invention is concerned primarily with mechanical apparatus for intimately mixing small batches of ingredients as for instance, medicinal powders for 5 apothecary use or the ingredients to form an amalgam for dental use with which latter application, the embodiment shown in the drawings and hereinafter described in detail, is more especially concerned.

10 It is among the objects of the invention to provide mixing apparatus of the character mentioned, of simple and compact construction, which shall be thoroughly sanitary in use.

15 Among other objects are to provide amalgam mixing apparatus of the character mentioned by which homogeneous amalgam of proper consistency is easily produced, unadulterated with traces of metal from 20 any part of the structure of the apparatus, in which the progress of the amalgamation may be observed throughout and which lends itself readily to operation from an ordinary dental engine.

25 According to my invention, the amalgam is mixed by the operation of projecting the ingredients, usually mercury and powdered silver against the wall of a container, thereby causing the mercury to sub-divide into 30 small particles and to offer a greater surface of contact with respect to the silver powder for more rapid and homogeneous amalgamation therewith. In the preferred apparatus for carrying out the process, a small 35 vial may serve as the container for the metal batch and be attached by means of its closure cap to a shaft which bears a driving spindle carrying at its inner end a mixing blade which preferably is of bone, ivory, 40 celluloid, bakelite, vulcanite or similar rigid non-metallic, non-corrosive material, and the edges of which substantially contact the walls of the vial.

45 In the accompanying drawings in which is shown one of various possible embodiments of the several features of the invention,

50 Figure 1 is a side elevation of the assembled amalgam mixer,

55 Figure 2 is a sectional view taken along the line 2-2 of Figure 1,

60 Figure 3 is a sectional view taken along the line 3-3 of Figure 1,

Figure 4 is a perspective view of the mixing blade,

55

Figure 5 is a side elevation of the driving spindle and,

60

Figure 6 is a view in longitudinal section of the haft.

65

Referring now to the drawings, I have shown a vial 10 which may be of glass or quartz preferably with a fairly thick wall and of uniform internal diameter from end to end. The vial is removably threaded into a vulcanite cover cap 11 which in turn has axially threaded thereinto a stud 12 formed integrally on a metallic haft 13 which is thereby firmly secured to the cap. The haft is adapted to be telescoped over the tool handle member 15 of any ordinary dental engine (not shown). The flexible shaft (not shown) of the dental engine is coupled by the usual clutch (not shown) with a driving spindle 16 extending axially of the haft into the vial and having a bearing 17 in the thick walled reduced end 18 of the haft. The driving spindle is retained against longitudinal displacement by a nut 19 threaded upon one end thereof and abutting shoulder 20 on the haft and nut 21 at the other end thereof abutting the inner surface of the cap 11. Upon the inner end of the driving spindle, I mount a substantially flat blade 23 which is generally rectangular in form, but is preferably thicker and stronger at its supported end and tapers in thickness to a relatively thin edge 24. The width of the blade is preferably substantially equal to the inner diameter of the vial, so that it substantially contacts the wall thereof and the blade has a threaded axial socket 27 into which the end of the spindle 16 is threaded so that its end edge 24 may substantially contact the bottom of the vial. Preferably a lock nut 25 is provided on the spindle by which the blade is held in a definite setting thereon contacting the bottom of the particular vial employed as indicated in Figure 2.

70

100

In assembly the nut 19 is first applied to the spindle 16, and the latter is then inserted through the end of the haft to bring nut 19 into contact with shoulder 20. The cap 11 is threaded to haft stud 12 whereupon the nut 21 is applied to combine the spindle and haft in an assembly. There-

105

after the nut 25 is applied to the spindle and finally the blade 23 is threaded in place and adjusted in position so that when the vial 10 is threaded into cap 11 the edge 24 of the blade will substantially touch the bottom of the vial. When the blade is thus in proper adjustment, the nut 25 is tightened thereagainst to lock it against shift and the assembly is completed.

10 For use, the haft 13 is applied to the tool handle 15 of a dental engine and the spindle 16 is coupled with respect to the flexible operating shaft of the dental engine. Thereupon the appropriate quantity of mercury 15 and powdered silver to form the amalgam is placed into the vial 10, the vial is applied to the cap 11 and the dental engine is set into operation. In this operation the blade 23 will revolve rapidly about its axis and by 20 reason of its close contact with the side wall and bottom of the amalgam, it will project the metallic contents against and about the wall of the vial, causing the liquid mercury to subdivide into small particles presenting a 25 relatively large exposed area for contact with the silver powder which is also agitated by the blades 23 and thus becomes rapidly amalgamated therewith. The completion of the operation will be apparent when 30 the material is visible through the vial as a unitary pellet and will also be noted from the operation of the engine. When the mixing operation is completed, after stopping the engine, the vial is removed from its cap 35 and the amalgam removed therefrom.

The effective length of the blade need not be that of the vial but it may as shown for instance in Figure 4 be shorter and have a unitary bushing extension 26 into which part 40 of the metal spindle 16 is threaded, the end of said spindle extending into the threaded socket 27 as in Figure 2. The vial is preferably suspended slightly inclined from vertically downward in operation so that in the 45 mixing, both the bottom and the side of the blade enter into engagement with the ingredients to more rapidly complete the amalgamation.

It will be especially noted that the ingredients of the amalgam throughout the mixing operation come into contact only with the glass vial and the bone, ivory, celluloid, bakelite, or vulcanite mixing blade so that the danger is wholly obviated of alloying 50 therewith any foreign metal which might be incurred in a mixer affording heavy metallic cups, sockets, anvils against which a cutting or crushing tool presses the ingredients that form the amalgam.

55 The amalgam when produced with my apparatus and according to my agitating or projecting method moreover has qualities superior to those of amalgams made by a crushing or cutting operation.

60 It will be understood that the haft and the

driving spindle would be constructed to correspond to the handle and flexible shaft of the dental engine and different securing means, clutches or lengths of spindle would be provided for different makes of dental engines.

70 While I prefer the specific construction shown and described, for operation from a dental engine, certain of the broader features of the invention are more generically applicable in other relations for operation by hand, for instance, or from miniature electric motors, not necessarily associated with dental engines and such construction would be more particularly applicable to powder 75 mixers for use by apothecaries.

80 It will thus be seen that there is herein described apparatus in which the several features of this invention are embodied, and which apparatus in its action attains the various objects of the invention and is well suited to meet the requirements of practical use.

85 As many changes could be made in the above construction and many apparently 90 widely different embodiments of this invention could be made without departing from the scope thereof, it is intended that all matter contained in the above description or shown in the accompanying drawings shall 95 be interpreted as illustrative and not in a limiting sense.

10 Having thus described my invention what I claim as new and desire to secure by Letters Patent is:—

1. An amalgam mixer comprising a generally cylindrical vial, a cover removably secured thereon, a non-metallic rotatable blade generally rectangular in form having a driving shaft extending axially through 10 said cover, the sides of said blade substantially contacting a wall of the vial in operation.

15 2. In an amalgam mixer, in combination, a generally cylindrical vial, a cover threaded thereon, a blade generally rectangular in 11 form, its side walls substantially contacting the side wall of the vial, a driving shaft for said blade extending axially through said cover, said blade adjustable on said driving shaft for proper positioning with respect to 11 said vial to bring the end of said blade substantially in contact with the end of said vial.

12 3. In an amalgam mixer, in combination, a metallic haft adapted to be attached to the tool holder of a dental engine handle, a driving spindle extending axially through said haft and bearing therein, stop nuts on said spindle preventing longitudinal movement thereof with respect to said haft, a rotatable non-metallic agitator threaded upon 12 the end of said shaft, and a non-metallic container removably secured to said haft for enclosing the amalgam to be mixed and also said agitator.

13 4. In a dental amalgam mixer of the type 13

adapted to be driven from a dental engine, in combination, a haft member attachable to the tool holder of the engine, a driving spindle having a bearing in said haft member and adapted to be connected to the engine shaft, a mixing blade rigidly secured to said spindle, a threaded cap secured to said haft member about said spindle and beyond the end of said blade, and a vial 10 surrounding said blade and threaded with respect to said cap.

5. In a dental amalgam mixer, in combination, a metal haft adapted to be attached to a dental engine tool handle, a vial cap 15 threaded upon the end of said haft, a driving shaft spindle extending axially through said haft, a stop upon said spindle against a shoulder in said shaft and a nut threaded on said spindle against the inside of said cap, 20 thereby to maintain the spindle against reciprocating movement, said spindle having a bearing in said haft and being adapted to be connected to the driving shaft of a dental

engine, a non-metallic mixing blade threaded upon the free end of said spindle, and a vial 25 enclosing said mixing blade and threaded into said vial cap, said blade extending substantially into contact with the side walls and bottom of said vial.

6. A dental mixing device embodying a 30 mandrel and a container, a threaded socket connection between the said mandrel and container, an agitator within the container, and a shaft extended through said mandrel and detachably connected with the agitator, 35 and a detachable connection between the mandrel and socket.

7. A dental mixing device embodying a 40 mandrel, and a container, a threaded connection between the same, an agitator within the container, and a shaft extended through the mandrel and socket and detachably connected with the agitator.

Signed at New York in the county of New York and State of New York A. D. 1925.

HENRY LEVY.
